WINCH CONSTRUCTION

Nils Gabel, Stockholm, Sweden

Application January 22, 1948, Serial No. 3,692

6 Claims. (Cl. 254—150)

1

This invention relates to an improved, manually operated winch which, while adaptable for many uses, is particularly suitable for expeditiously adjusting the stays of racing boat masts and the like.

Heretofore the operation of adjusting the mast stays has been carried out by hand. Since time is of the essence during a race and since speed and expeditiousness in manipulation of the boat may determine the difference between a victory and a defeat in the final outcome, it is highly advantageous to have an easy and rapid method of adjusting the mast stays.

Accordingly, it is an object of the present invention to provide a winch which may be conveniently mounted in pairs in the cockpit or at the helm of the boat, one winch controlling the starboard backstay and the other winch controlling the port backstay.

Another object of the invention is the provision of a winch having a base support carrying a winding drum freely rotatable thereon, an unidirectionally rotatable wheel element and means for rapidly engaging and disengaging the wheel element from the freely rotatable winding drum for alternately tightening and slackening the stay or cable fixed to said winding drum as required.

The foregoing objects as well as additional objects and advantages of the invention will be readily apparent in the course of the following detailed description taken in conjunction with the accompanying drawings which illustrate preferred embodiments of the invention and wherein:

Fig. 1 is a top plan view of a winch embodying the features of the invention, parts being broken away for the sake of clarity;

Fig. 2 is a vertical sectional view taken along lines 2—2 of Fig. 1;

Fig. 3 is a top plan view of an alternative form of winch, the hub being partly broken away to reveal internal structure;

Fig. 4 is a vertical sectional view taken along lines 4—4 of Fig. 3; and

Fig. 5 is a sectional view taken along lines 5—5 of Fig. 4 and showing the apertured top flange of the winding drum.

Referring first to the embodiment of the invention illustrated in Figs. 1 and 2, the winch is shown as comprising a base support 10 having a central shaft portion 11 upon which a winding drum 12 is freely rotatable. Winding drum 12 is provided with an upper flange having a plurality of radially extending teeth 13 for a purpose to be

2

fully described hereinafter. Shaft 11 is provided with an upper mounting flange 14 for retaining a control wheel 15 thereupon, said mounting flange being secured by means of a screw or in any other suitable manner.

Control wheel 15 may be formed with an outer rim 16, radial spokes 17 and a hub 18 having an enlarged collar portion 19 defining a recess for the reception of mounting flange 14 of shaft 11.

10 Means is provided for preventing the rotation of control wheel 15 except in a clockwise direction as seen in Fig. 1. This latter means may conveniently take the form of a pair of braking elements 20 pivotally secured to the mounting flange 14 by means of pivot pins 21, each of said braking elements having an outer cam-braking surface 20a arranged to abut the inner wall of the collar portion 19 of the hub 18 and exert a wedging action to prevent counter clockwise rotation or recoiling of control wheel 15.

15 The inner end of each braking element 20 is preferably provided with a lug 22 and a coil spring 23 interconnects said lugs to normally urge the cam-braking surface 20a of each braking element 20 outwardly against the inner wall of the collar portion 19 of the control wheel 15. Clockwise rotation of said control wheel is permitted by the slight pivotal movement of braking elements 20 about pivots 21, cam surfaces 20a slipping against the inner wall of the collar portion 19 as the wheel 15 is turned. Manipulation of wheel 15 may be facilitated by means of a handle 16a suitably mounted on rim 16.

20 It is necessary to provide means for engaging 35 and disengaging the unidirectionally rotatable wheel 15 with the freely rotatable winding drum 12 for alternately tightening and slackening the stay or cable (not shown) secured to said winding drum. This means may take the form of a lever 24 pivoted between a pair of upstanding

25 lugs 25 on the wheel spoke 17 and extending 40 downwardly through a slot (not shown) in spoke 17 for a sufficient distance to enter between an adjacent pair of teeth 13 on winding drum 12.

45 Lever 24 is preferably provided with an upper handle portion 24a by means of which said lever may be manipulated into and out of engagement between any adjacent pair of teeth 13 for alternately engaging and disengaging winding drum 50 12 with the unidirectionally rotatable control wheel 15. A toggle linkage 26 may be secured to lever 24 for retaining said lever in its effective "in" and "out" positions.

55 It will be understood that one end of the stay or cable is secured in any preferred manner to

the winding drum 12. When it is desired to tighten the stay or cable, lever 24 is brought into engagement between an adjacent pair of teeth 13 on winding drum 12 whereupon both wheel 15 and said winding drum may be rotated in a clockwise direction to tighten the stay or cable to any desired extent, the wedging action of braking elements 20 within the collar portion 18 of the hub 19 serving to prevent counter clockwise rotation of the wheel 15 and unwinding of the cable. On the other hand, when it is desired to slacken the stay or cable, lever 24 is disengaged from between an adjacent pair of teeth 13 on drum 12 by depressing handle portion 24a, thereby restoring said drum to its freely rotatable condition and allowing the cable or stay to loosen thereupon.

The winch may be secured to the cockpit wall or adjacent the helm of the boat by means of mounting holes 10a in base support 10 or in any other desired manner. A cover plate or cap 27 may be threadedly engaged at the top of collar portion 19 of hub 18. It is to be understood that where the winch is employed for adjusting the backstays of the mast of a boat, a pair of winches will be necessary, one for each backstay, and the pair of winches may be conveniently positioned for simultaneous operation using both hands to accomplish the desired adjustment instantaneously.

Referring now to the embodiment of the invention illustrated in Figs. 3-5, there is shown a base support 30 having a central shaft portion 31 for retaining thereupon a normally freely rotatable winding drum 32 having an upper flange 33 provided with a plurality of apertures 34 for a purpose to be hereinafter indicated. A disc 35 having an annular groove 36 is fixedly mounted at the end of the shaft 31 as by means of pins 37 and screw 38. A control wheel 39 comprising a rim 40, a handle 41, spokes 42 and an open-bottom hub 43 is provided for the winch, said wheel being rotatable on disc 35 by means of arms 44 pivoted to the hub 43 by means of pivot pins 45 and being partially retained within the annular groove 36 of said disc. Each arm 44 is normally retained within groove 35 by the action of a leaf spring 46 supported at one end by an integral projection 47 of the hub 43 and bearing against said arm at its other end.

Counterclockwise rotation of wheel 39 is prevented by the wedging action of arms 44 against the sides and bottom of annular groove 36, each of said arms being provided with an inner cam surface abutting the bottom of said groove. Because of the relative disposition of arms 44 with respect to groove 35 no wedging or braking action occurs upon clockwise rotation of wheel 39, the inner cam surfaces 44a of each arm 44 merely slipping against the groove 36 with the rotation of said wheel.

As in the initial embodiment described hereinabove means is provided for alternately engaging and disengaging the unidirectionally rotatable wheel 39 with the freely rotatable winding drum. As has been previously pointed out, winding drum 32 has an upper flange 33 provided with a plurality of apertures 34. A retractable plunger 48 is mounted within a bore of hub 43 and is actuated by a cam lever 49 for alternate insertion within and retraction from any given aperture 34 in order to engage and disengage wheel 39 and drum 32 for respectively tightening and slackening the cable or stay (not shown) which is fixed to said drum. Plunger 48 has a

central slot extending downwardly from the top surface thereof and is further provided with a hollow bore for the reception of a spring 51, the upper end of which rests against a bridge piece 50. Cam lever 49 is pivoted at 52 to the plunger 48 and when said lever is raised, the low point of the cam abuts against the top of bridge piece 50, allowing the plunger 48 to enter one of the apertures 34. On the other hand when cam lever 49 is lowered, plunger 48 is retracted to disengage wheel 39 from operative connection with winding drum 32.

While the winch of the invention has been described in connection with its application to the adjustment of the mast stays of a racing boat or the like, it is obvious that it is capable of many other applications.

Since certain modifications may be made in the winch of the invention without departing from the scope thereof, it is intended that all matter contained in the foregoing specification and shown in the accompanying drawing be interpreted merely as illustrative and not in a limiting sense.

What is claimed is:

1. A winch comprising a base having a central shaft portion, a winding drum freely rotatable upon said shaft portion, a disc having an annular groove therewithin fixed to the end of said shaft portion, a control wheel unidirectionally rotatable upon said disc and having an open-bottomed hub, arms pivoted to said hub and being partially retained within said groove, a spring normally urging each of said arms towards said groove, each of said arms having a cam surface abutting said groove for wedging action to prevent counter-rotation of said wheel, said winding drum having an upper flange provided with a series of spaced apertures, and a retractable plunger carried by said wheel and insertable within one of said apertures, whereby to selectively engage and disengage said winding drum from operative connection with said control wheel.

2. A winch comprising a base having a central fixed shaft portion, a winding drum freely rotatable upon said shaft portion, a control wheel unidirectionally rotatable upon said shaft portion and having a hub portion defining a recess between said hub and said shaft, pivoted braking elements disposed in said recess, a spring member for retaining said braking elements within said recess, each of said braking elements presenting an operative cam surface for wedging action between said hub and said fixed shaft to prevent counter-rotation of said control wheel, and releasable locking means cooperating between said control wheel and said winding drum for selectively engaging and disengaging said winding drum from operative connection with said control wheel, whereby to maintain said winding drum under load and prevent unwinding upon the removal of the force applied to the engaged control wheel unless said locking means is released.

3. A winch in accordance with claim 2 wherein said winding drum is provided with a plurality of radially extending teeth and said releasable locking means comprises a lever pivotally secured to said wheel and engageable between an adjacent pair of said teeth.

4. A winch in accordance with claim 2 wherein said winding drum is provided with a flange having a series of spaced apertures and said releasable locking means comprises a retractable plunger

er carried by said wheel and selectively insertable within one of said apertures.

5. A winch comprising a base having a fixed central shaft, a winding drum freely rotatable upon said shaft, a disc having an annular groove therewithin fixed to the end of said shaft, a control wheel unidirectionally rotatable upon said disc and having a recessed hub, spring-urged arms pivoted to said hub and slidably retained within said groove during the said unidirectional rotation of said control wheel, each of said arms having a cam surface abutting said groove for wedging action to prevent counter-rotation of said wheel, and releasable locking means cooperating between said control wheel and said winding drum for selectively engaging and disengaging said winding drum from operative connection with said control wheel.

6. A winch comprising a base having a fixed central shaft, a winding drum freely rotatable upon said shaft, a disc having an annular groove therewithin fixed to the end of said shaft, a control wheel unidirectionally rotatable upon said disc and having a recessed hub, spring-urged

arms pivoted to said hub and slidably retained within said groove during the said unidirectional rotation of said control wheel, each of said arms having a cam surface abutting said groove for wedging action to prevent counter-rotation of said wheel, said winding drum being provided with a plurality of radially extending teeth, and a lever pivotally secured to said wheel and engageable between an adjacent pair of said teeth, whereby to selectively engage and disengage said winding drum from operative connection with said control wheel.
